UNITED STATES PATENT OFFICE

THOMAS P. GREGER, OF PHILADELPHIA, PENNSYLVANIA.

DESIGN FOR A MANHOLE-COVER.

SPECIFICATION forming part of Design No. 27,674, dated September 21, 1897.

Application filed August 3, 1897. Serial No. 646,983. Term of patent 14 years.

To all whom it may concern:

Be it known that I, THOMAS P. GREGER, a citizen of the United States, residing at the city of Philadelphia, in the county of Philadelphia and State of Pennsylvania, have invented and produced a new and original Design for Manhole-Covers, of which the following is a specification, reference being had to the accompanying drawings, forming a part thereof.

Figure 1 is a top or plan view of a manhole-cover showing my design, and Fig. 2 is a central vertical sectional view of the same.

The leading feature of my design consists in the raised annular rib-like projections, which when viewed in plan, as in Fig. 1, are arranged entirely within a substantially circular outline and in series concentric with said outline and which when viewed in section, as in Fig. 2, appear to project upward from a concave base.

Referring to the drawings, A is the base of the manhole-cover, which in outline is substantially circular and in vertical section is

dish shape or concave. From this concave base A extend the annular rib-like projections B, in series of two or more, all arranged within the circular outline and concentric therewith and with each other, thus dividing the circular base into a series of rings D, so that the cover when viewed in plan presents to the eye the combined effect of a circular field divided into a number of concentrically arranged rings between which asphaltum, granolithic or other matter is adapted to be packed.

Having thus described my invention, what I claim as new, and desire to secure by Letters Patent, is—

The design for a manhole-cover, substantially as shown and described.

In testimony whereof I have hereunto set my signature in the presence of two subscribing witnesses.

THOMAS P. GREGER.
